VALVE-OPERATING MECHANISM

Application filed April 4, 1930. Serial No. 441,654.

My invention relates to means for effecting operation of the valves of an internal combustion engine. Heretofore it has been the customary practice to leave a slight clearance between the valve stem and the tappet or between the push rod and tappet, as the case may be. Due to this clearance the action of the valve mechanism is noisy (the clearance increasing with wear), the volume of noise generated being proportional in large measure to the degree of clearance provided between the parts.

Many attempts have heretofore been made to solve the problem of overcoming such objectionable feature. All those attempts with which I am familiar appear to have been lacking in one or another particular since none of them seem to have come into substantial use in the art.

It is an object of my present invention to provide means always to maintain contact between the valve stem (or push rod) and the tappet and to make provision to allow for expansion and contraction and take up wear of parts automatically.

Further, it is an object to provide an improved valve tappet embodying certain features in virtue of which the valve noise so frequently accompanying the running of an internal combustion engine is practically entirely eliminated.

Further, it is an object to provide a valve tappet containing the advantageous features aforesaid in which all moving parts are so designed to permit their effective lubrication through the usual lubricating system of the engine, i. e., requiring no special provisions for lubrication.

Other objects will be in part obvious and in part be pointed out hereinafter.

To the attainment of the aforesaid objects and ends, the invention still further resides in the novel details of construction, combination and arrangement of parts, all of which will be first fully described in the following detailed description, then be particularly pointed out in the appended claims, reference being had to the accompanying drawing, in which:—

Figure 1 is a vertical longitudinal section

illustrating my invention, the parts being in the position they assume when the valve is seated.

Figure 2 is a similar view, the parts being in the position they assume when the cam has raised the tappet to open the valve.

Figure 3 is a cross section on the line 3—3 of Figure 1.

Figure 4 is a cross section on the line 4—4 of Figure 1.

Figure 5 is a perspective view of the split member.

In the drawings, in which like numerals of reference indicate like parts in all of the figures, 1 represents the cam shaft whose cam 2 is designed to engage the base 5 of the tappet body 4, the latter being cylindrical in form and of tubular structure and mounted to slide in the bearing 3 of the engine. Within the tubular body 4 there is mounted a split member consisting of a base 8 from which projects upwardly a tubular portion 7, that is provided at its upper outer portion with a cylindrical contacting or gripping face 9 and is provided with an internal conical expanding or clutching face 11. Beneath the clutching face 11 the split member 7 has a cylindrical chamber 12 in which a coil spring 16 is disposed.

The base 8 has a snug sliding fit within the tubular body 4 while the face 9 normally has a slight clearance from the body 4. The member 7 is made of such material that the split portions thereof will continuously tend to approach each other or contract toward the center, thereby maintaining the conical clutching surface 11 continuously in contact with the clutch portion 14 of the plunger member 13, the latter having a stem 15 that lies within the chamber 12.

10 designates the longitudinal splits in the member 7.

The plunger member 13 is bored and tapped as at 17 to receive the adjusting screw 18 whose head 19 contacts the end of the valve stem 21 and whose threaded portion is provided with a jam nut 20 as shown.

The valve stem 21, spring holding cap 23, retaining clip 22, and spring 24 may all be of any of the usual constructions and

per se constitutes no part of the present invention.

Preferably I make the top of the head 19 of the adjusting screw 18 convex so as to facilitate the wiping action of the cam which tends to turn the tappet on its longitudinal axis in its bearing 3 to prevent undue wear.

In operation, when the engine is cold the adjusting screw 18 is so adjusted that the surfaces 11 and 14 will be in contact without bringing the surface 9 into contact with the internal surface of the member 4. The adjustment is also so made that the valve stem 21 will be in contact with the head 19 of the adjusting screw. With the parts in this position, as the cam shaft rotates and forces the tappet upwardly, the cone clutch surfaces 11 and 13 will cause the split end of the member 7 to expand laterally, thereby bringing the surface 9 into tight contact with the inner wall of the member 4 and securely lock these parts together during the upward thrust of the tappet.

On the downward stroke of the tappet the parts will remain in this position until the valve has seated which will occur just prior to the time when the base 5 has reached the limit of its downward movement. The slight additional movement (which was allowed for in valve clearance in the old practice) is taken up by the contraction of the split member 7 and the consequent forcing down of that member and the member 4 while the plunger member is held up by the spring 16 into contact with the valve stem 21.

By my arrangement it will also be seen that the oil accumulating from the bearing 3 will overflow into the member 4 and substantially fill it. In order to prevent stagnation of this oil a drain hole 6 may be provided in the base 5 through which the oil may gradually flow and also assist in lubricating the line of contact between the cam 2 and the base 5. The presence of the oil in the cylinder 4 also assists in damping any possible noise that might take place due to the slight clearance between the surface 9 and the internal surface of the member 4.

Tests have shown that a valve mechanism embodying my present invention can be run at exceedingly high speeds and all valve tapping noise eliminated.

While I have illustrated my invention specifically as embodied in a tappet, it is obvious that it may also be embodied in the push rod structure or in the connection between the rocker arm and the valve stem of an overhead valve type of engine. As such modifications of the invention would be mere changes in form and not in substance, illustration thereof is thought to be unnecessary.

From the foregoing description, taken in connection with the accompanying drawing, it is thought the construction, operation and advantages of my invention will be clear to

those skilled in the art to which it relates.

What I claim is:

1. In valve operating mechanism, the combination with the tappet operating cam and the valve stem of an engine; an operating means located between said cam and stem and including a tubular body, a bearing in which said body has a reciprocating sliding fit, said body having an opening in its top, a split tubular member fitted within said body and having a cone-clutch area within one end and a body contacting area on its outer surface, a plunger member having a clutch portion and a stem to fit within said split tubular member, and a spring within said split tubular member for engaging said stem and tending to separate said plunger from said split tubular member. 70
75

2. In valve operating mechanism, a valve tappet comprising a cylindrical body having a cam-engaging base at one end and being open at the other end, a valve stem contacting plunger member including a cone-clutch portion and a stem portion to project into said cylindrical body, and means in said cylindrical body embracing said plunger member for maintaining a continuous metal-to-metal connection between said cylindrical body and said plunger member, said plunger member adapted to contact the valve stem at all times. 85
90

3. In valve operating mechanism, a valve tappet comprising a cylindrical body having a cam-engaging base at one end and being open at the other end, a valve stem contacting plunger member including a cone-clutch portion and a stem portion to project into said cylindrical body, and means in said cylindrical body embracing said plunger member for maintaining a continuous metal-to-metal connection between said cylindrical body and said plunger member, said plunger member adapted to contact the valve stem at all times, said last named means comprising a split tubular body fitted within said cylindrical body and having a cone-clutch face continuously tending to contact with said cone-clutch portion of said plunger member, said split body being forced into tight contact with the wall of said cylindrical body when pressure is applied tending to force said plunger member into said split body. 100
105
110

4. In valve operating mechanism, a valve tappet comprising a cylindrical body having a cam-engaging base at one end and being open at the other end, a valve stem contacting plunger member including a cone-clutch portion and a stem portion to project into said cylindrical body, and means in said cylindrical body embracing said plunger member for maintaining a continuous metal-to-metal connection between said cylindrical body and said plunger member, said plunger member adapted to contact the valve stem at all times, said last named means comprising 115
120
125
130

a split tubular body fitted within said cylindrical body and having a cone-clutch face continuously tending to contact with said cone-clutch portion of said plunger member,
5 said split body being forced into tight contact with the wall of said cylindrical body when pressure is applied tending to force said plunger member into said split body, and means continuously tending to separate
10 said plunger member from said split body.

5. In valve operating mechanism, a valve tappet comprising a cylindrical body having a cam-engaging base at one end and being open at the other end, a valve stem contacting
15 plunger member including a cone-clutch portion and a stem portion to project into said cylindrical body, and means in said cylindrical body embracing said plunger member for maintaining a continuous metal-to-metal con-
20 nection between said cylindrical body and said plunger member, said plunger member adapted to contact the valve stem at all times, said last named means comprising a split tubular body fitted within said cylindrical
25 body and having a cone-clutch face continuously tending to contact with said cone-clutch portion of said plunger member, said split body being forced into tight contact with the wall of said cylindrical body when pressure
30 is applied tending to force said plunger member into said split body, and means continuously tending to separate said plunger member from said split body, said last named means comprising a spring within said split
35 tubular body for engaging the stem portion of said plunger member.

6. A valve tappet for internal combustion engines, comprising a tubular body having a cam-engaging base at one end and being open
40 at the other end, a member comprising a base portion fitted within said body and a longitudinal split tubular portion whose end remote from said base portion is provided with an internal cone seat and with an external
45 gripping surface, the latter being adapted to engage the adjacent inner surface of said tubular body when said split portion is expanded, a plunger element for contacting with a valve stem and projecting into said
50 split tubular portion and having a cone surface to engage with said cone seat for expanding said split tubular portion into engagement with the wall of said tubular body when said plunger member is forced inward-
55 ly, and yieldable means tending to force said plunger member outwardly.

JOHN NICHOLAS PERKINS.
